UNITED STATES PATENT OFFICE

2,086,003

TERMINAL DEVICE

Joseph H. Staley, Columbus, Ind.

Application December 2, 1935, Serial No. 52,538

3 Claims. (Cl. 173—324)

This invention relates to mercury tube switches and particularly to means for insulating metallic walls of such switches and also to applying pig-tail terminals. An important advantage of the invention is that the metallic wall switch may be made to be interchangeable with glass wall switches without having to change mountings and the like.

A further important advantage of the invention is that the metallic wall switch may be employed in damp places or places where much dust may accumulate so that by reason of the use of the invention, the two parts of the metallic wall comprising the electrodes of the switch may not be bridged over by moisture and dust. A further important object of the invention is to provide a very simple, efficient and low cost means for suitably insulating the metal wall switch all in a manner that will not detract from the operating efficiency of the switch even under severe conditions.

These and other advantages and objects of the invention will become apparent to those versed in the art in the following description of one particular form of the invention as illustrated in the accompanying drawing, in which

Fig. 1 is a side elevation of a structure embodying my invention;

Fig. 2, a longitudinal central section on the line 2—2 in Fig. 1;

Fig. 3, a view in perspective of one terminal piece;

Fig. 4, a view in perspective of a second terminal piece, and

Fig. 5, a transverse section on the line 5—5 in Fig. 2.

Like characters of reference indicate like parts throughout the several views in the drawing.

The particular mercury tube switch shown herein as one particular form to which my invention may be applied is that as illustrated in my Patent No. 1,906,118, issued April 25, 1933, wherein a body 10 forms one terminal or electrode by an exterior cylindrical surface and a cap 11 forms the other electrode by a similar cylindrical surface, the cap 11 being insulated from the body 10 by an intervening insulating member 12.

I provide a terminal piece generally indicated by the numeral 13, Fig. 3, having its major portion longitudinally corrugated or bent to provide the outer longitudinal edges 14 and 15 with an intervening central ridge 16. From one end of the member 13 is turned a tongue 17 herein shown as having a hole 18 through the tongue.

This member 13 is placed on the cap 11 to have the ridge 16 longitudinally contacting the cap with the edges 14 and 15 also contacting the longitudinal surface of the cap in spaced relation on the respective sides of the rib 16, whereby in fact, the terminal member 13 makes contact with the cap 11 along three lines.

A tubular piece 19 of insulating material having an internal diameter closely approximating the external diameter of the cap and body of the switch is then entered over the end of the cap 11 and around the outside of the member 13 and pressed longitudinally therealong so as to tend to compress the member 13 snugly against the cap 11 causing a concentrated pressure to be applied on the member 13 to bring it into forced line contacts with the cap. The tongue 17 is turned downwardly across the outer end of the cap 11 to serve initially as a limiting stop to prevent longitudinal travel of the member 13 along the cap 11 as the tube 19 is pressed thereover.

The body 10 is provided with a transverse slot 20 such as would be formed by sawing a kerf across the body. A second terminal member generally designated by the numeral 21, Fig. 4, has its major portion formed similarly to that of the piece 13 to have the central longitudinal ridge 22 with the outlying regularly up-turned edges 23 and 24. One end of this member 21 is provided with a short tongue 25 turned from the principal portion thereof while the other end is provided with a longer tongue 26 herein shown as having a hole 27 therethrough.

This member 21 is placed on the body 10 to have the tongue 25 entering the slot 20 and the tongue 27 hanging over the outer end of the body. As the tube 19 is forced along from the cap 11 and over onto the body 10, it will pass over the member 21 tending to compress it snugly against the side of the body 10 and bring it into the three line contact therewith as determined by the center line 22 and the outer lines of the edges 23 and 24. The tube is pressed on over the member 21 until it extends at least to the outer end of the body 10 and preferably a slight distance therebeyond. By reason of the tongue 25 engaging in the slot 20, the member 29 is not shifted along the body 10 but is held firmly in position thereon as the tube 19 slides over the member 21.

The terminal members 13 and 21 are made out of any suitable electrically conducting metal. The tube 19 is made out of any suitable insulating material having a slight resiliency or at least

sufficient resiliency to prevent the tube from tearing or breaking as it is pressed over the members 13 and 21 and also as will cause it to permanently retain the members 13 and 21 in compressive contact with the cap and body of the switch. One suitable material for the tube 19 is a vulcanized or thermo-plastic material formed in conjunction with paper or fiber.

A pigtail 28 has one end of its conductor 29 attached to the terminal member 13 as indicated in Fig. 2 and is preferably soldered thereto. Likewise the pigtail 30 is connected to the other terminal member 21 to form an electrical connection therewith such as by soldering the conductor 15 31 to the tongue 26, the holes in the respective tongues 17 and 26 aid in permitting engagement of the conductors therewith and in the soldering operation. The tube 19, while not necessarily so, is preferably cut to a length to extend slightly 20 beyond the outer end of the cap 11 as indicated in Fig. 2 so as to provide an outer wall to confine an insulating medium which is employed to cover over the end of the cap. An insulating composition which is plastic initially is applied to the end 25 of the cap 11 and carried outwardly along the pigtail 28 a sufficient distance such that when the material sets, the pigtail so surrounded by that material will be held rigidly and not permitted to bend therewithin, thus protecting the connection 30 of the pigtail with the member 13. This insulating composition indicated by the numeral 32 is commercially called cable lacquer and is well known for the purpose and is of that nature which will set and harden but not become so 35 rigid as to lose its resiliency. Similarly the material 32 is filled in accordance with the end of the body 10 and built out a slight distance around the pigtail 30 all as indicated in Fig. 2.

The tube 19 preferably has a comparatively

thin wall and is also preferably made in a black color with a dull finish so as to permit rapid heat radiation whereby heat arising within the switch due to arcing may be readily dissipated and not allowed to build up within the switch.

While I have herein shown and described my invention in one particular form, it is obvious that structural variations may be employed without departing from the spirit of the invention and I, therefore, do not desire to be limited to that precise form beyond the limitations as may be imposed by the following claims.

I claim:

1. A terminal member having a major elongated portion with a longitudinal corrugation and both edges parallel with the corrugation bent in the same direction as the corrugation and a tongue formed by bending an uncorrugated end of the member transversely of the corrugated portion.

2. In combination with a cylindrical metallic envelope, a cylindrical insulating sleeve telescoping the envelope, and a terminal member superficially carried between the sleeve and the envelope, said terminal member having a major portion comprising two corrugations on one side and a single corrugation on the other between the two forming a three-line contact with the respective envelope part under pressure exerted by the surrounding sleeve.

3. In combination with a metallic envelope, an insulating sleeve, and a terminal member carried between the sleeve and the envelope, said terminal member having a portion corrugated in effect whereby said sleeve may press said portion around a curving wall of the envelope into three lines of contacts therewith.

JOSEPH H. STALEY.
